UNITED STATES PATENT OFFICE.

HERMANN THEODOR FRIEDRICH GAST, OF CARLISLE, ENGLAND.

APPARATUS FOR CLEANING HAIR-BRUSHES.

1,152,168.

Specification of Letters Patent. Patented Aug. 31, 1915.

Application filed January 16, 1915. Serial No. 2,729.

To all whom it may concern:

Be it known that I, HERMANN THEODOR FRIEDRICH GAST, residing at 206 Greystone road, Carlisle, in the county of Cumberland, England, have invented certain new and useful Improvements in Apparatus for Cleaning Hair-Brushes; and I do hereby declare the following to be a full, clear, and exact description of the invention, such as will enable others skilled in the art to which it appertains to make and use the same.

This invention relates to apparatus for cleaning hair brushes of the kind wherein a perforated or open grid-like surface is provided in conjunction with angularly disposed combs or the like at the ends of said perforated or grid-like surface, whereby upon the brush being moved to and fro thereover, hair is caught by the combs while any scurf or other foreign matter is extracted by the grid-like surface and falls therethrough into a tray or container.

The object of the present invention is to provide apparatus of this kind whereby suitable cleansing or disinfecting liquid is imparted to the brush during the cleaning operation, and to provide an apparatus of generally improved construction.

To this end the invention consists in the combination, with the perforated or open grid-like surface and a comb or combs, of a suitable container or containers adapted to receive some suitable disinfecting or other liquid, having a wick or wicks or like medium disposed in such position that, as the brush is moved thereover, the liquid is imparted, in a more or less fine spray to the bristles for the purpose of cleansing same or imparting a pleasant odor thereto.

The accompanying drawings illustrate some forms of the apparatus made in accordance with the invention, in which:

Figure 1, is a cross section of the apparatus open for use; Fig. 2, is a plan thereof, partly in section with part removed; Fig. 3 is a section on line A—A of Fig. 2; Figs. 4, 5 and 6 are details to an enlarged scale, and Figs. 7 and 8 are longitudinal sections of modified forms.

Referring first to Figs 1 to 6 *a* is the box-like case having a hinged lid or cover *a*¹ within which casing *a* is disposed a tray *b* of about the same depth as the internal depth of the casing. Within the tray *b* is detachably disposed a frame *c* having a grid-like top composed of a plurality of spaced

rods *d*. The frame *c* is adapted to project slightly above the tray *b* in which position it is supported upon shoulders or the like *e* formed in the corners of said tray. 60

f are the combs disposed at each end of the frame which may be secured in any desired manner, and of any desired form, the ends of the teeth of which are preferably formed with comparatively sharp points so 65 as not to damage the bristles of the brush when passed thereover.

As shown more especially in Figs. 3 and 6 the teeth of the combs are mounted in a backing *f*¹ which is in turn carried in a tubular member *g* the teeth projecting through a longitudinal slot formed therein. The ends of the tubular members *g* are mounted in holes or recesses formed in the side walls in the framing *c* whereby the combs may be 70 adjusted to the desired angular position and then clamped in said position by means of tapered screw plugs *h* which when screwed home expand the split end of the tubular part *g* within the holes or recesses in which 75 the tube is mounted.

i is a box or container of somewhat triangular cross section the flat upper surface of which is closed by a cover or lid *j* in which is formed a slot or a wick holder *j*¹, a washer 80 of suitable material *j*² being interposed between said cover and the flat top of the container. This box or container *i* is adapted to be detachably secured to the frame *c* the side members of which are recessed as at *k*, 90 Fig. 2, so as to allow the wick to project just above the plane of the rods *d*.

l are two clamps in the form of light rods, passing under the container, the ends of which are bent upwardly at right angles 95 and adapted to be passed through holes in the frame *c* and provided with nuts *m*, the extremities of the rods *l* being screwed for the purpose whereby the container *i* is held firmly in position but which can be easily 100 removed when required for filling or cleaning purposes.

It will be seen that the clamps *l* also serve the purpose of holding the lid *j* tightly upon the container by pressing same against 105 the recessed or undercut portion of the frame *c*, a resilient seating or pad *n* being interposed at each end of the lid for the purpose.

Upon the inner side of the lid *a*¹ of the box or casing *a* is provided a cover *o* the edges of which are provided with a flexible portion *o*¹ of rubber or the like adapted

when the box is closed (as indicated in dotted lines Fig. 1) to press tightly upon the lid *j* to completely inclose the wick and prevent the escape or evaporation of the contents of the container *i* when not in use.

The lid *a*¹ may be provided with suitable perforations or holes *a*² to allow of the ventilation of the apparatus when closed.

Fig. 7 shows a modification wherein instead of employing one container in the center of the frame *c* two such containers may be provided one at each end beneath the combs *f* as indicated at *c*⁰, whereat they may be secured in similar manner to that already described in reference to the first mentioned construction or in any other suitable manner.

Fig. 8 shows a further modification wherein in one container *c*⁰ only, is provided, at one end of the frame *c*, which frame is also provided with one comb only, at the opposite end. The combs *f* in these last two constructions are mounted to the frame *c* by screws and nuts or otherwise.

It will be understood that instead of employing a series of spaced rods to form the open grid-like surface over which the brush is moved said surface may be formed in any other suitable manner as by network or perforation of any desired configuration or otherwise.

In use, as the brush to be cleansed is passed to and fro in contact with the grid-like surface and in contact with the wick or wicks, the bristles are caused to vibrate, which vibration causes the liquid from the wick to be imparted to and distributed

among said bristles in the form of a fine spray to effectually disinfect same.

What I claim and desire to secure by Letters Patent is:—

1. A brush cleaner, comprising a grid, a moistening device having an outlet which projects above the grid, a comb having its points arranged above the grid, and means for holding the said parts in position. 40

2. A brush cleaner, comprising a tray, a grid supported in the upper part of the tray, a moistening box for liquid secured in the tray and having an outlet which projects upwardly through the grid, and a comb secured to the grid and having its points arranged above it. 50

3. In a brush cleaner, a grid, a moistening device having an outlet which projects above the grid, a pivotally adjustable comb having its points arranged above the grid, and means for holding the said parts in position. 55

4. In a brush cleaner, a grid, a moistening device having an outlet which projects above the grid, a comb having its points arranged above the grid, a case inclosing the said parts and holding them in position and having a lid, and a cover of flexible material secured to the lid and adapted to be pressed over the outlet of the moistening device when the lid is closed. 60

In testimony whereof I affix my signature, in presence of two witnesses.

HERMANN THEODOR FRIEDRICH GAST.

Witnesses:

YVES MARIE LA GALL,
FREDERICK WILLIAM HALTON.
